CONTROL SYSTEM

Harold D. Roop, Los Angeles, Calif., assignor to
 Automatic X-Ray Corp., Los Angeles, Calif., a
 corporation of California

Application June 1, 1946, Serial No. 673,732

13 Claims. (Cl. 250—95)

1 My invention relates to the art of regulating voltage and has special reference to the automatic regulation of the operating voltage applied to X-ray tubes. This invention also relates to the regulation of the intensity of electromagnetic radiation, including the maintenance of constant X-ray transmission through non-uniform moving materials, a control which is essential for certain types of inspection.

The use of X-rays for irradiating materials to determine the physical and chemical properties thereof has become a very important industrial procedure which is employed for identifying defective manufactured products, for examining engineering materials, and for medical diagnosis and X-ray therapy. Metallurgical products are tested by transmitting X-rays therethrough to determine porosity, crystal growth, slag inclusions, gas pockets, or fissures.

In testing procedures which utilize X-rays for thickness gauging and certain other forms of automatic inspection and identification or segregation of defective articles, it is desirable to regulate an X-ray generator for the purpose of maintaining a constant output level of radiation intensity for the purpose of maintaining a constant transmission through a moving article or a series of such articles. This necessitates very rapid automatic modulation of the intensity of the radiation emitted by the generator, since the thickness or character of the irradiated materials may vary quite rapidly.

Practically all conventional X-ray equipment used for industrial inspection is of the half-wave or self-rectified type in which one-half of the electrical cycle is loaded and the other half unloaded. Conventional line voltage regulators such as the "Raytheon" or "Sola" type will not operate on this kind of unsymmetrical load. The only line voltage regulator available for such X-ray equipment is a motor driven auto-transformer actuated inversely by the variations in the line voltage for the purpose of compensating for line voltage drift and supplying constant average input power to an X-ray generator.

Although the line voltage controlled motor driven auto-transformer serves a useful purpose where a steady X-ray output is desired, it does not hold the supply voltage within the close limits required for automatic precision gauging and it cannot compensate for any factors within the generator that may cause output intensity to vary because it is actuated only by variations in the supply voltage. Furthermore, when made responsive directly to line voltage variations, it is

often incapable of the quick response required in many X-ray applications where predictable instantaneous values of radiation and rapid corrective action are essential.

5 The present invention contemplates a system whereby the voltage applied to the X-ray generator may be varied in response to changes in the radiation produced, e. g., the direct radiation from the X-ray tube or the radiation after transmission through an object. Heretofore no means has been commercially available for automatically maintaining a uniform intensity of X-ray transmission through an object of varying X-ray opacity, e. g., a moving object of non-uniform thickness passing through a X-ray beam for gauging or for the detection of flaws.

An important object of my invention is to provide a system whereby the radiation emitted by an A. C. operated X-ray generator is employed to maintain the intensity of the radiation emitted therefrom at a substantially constant level or to maintain substantially constant the transmitted radiation traversing an object to be tested, e. g., an object of non-uniform thickness or character.

I have discovered that the foregoing objectives of my invention may be achieved by utilizing the intensity of the beam of radiation emitted by an X-ray generator for actuating a voltage control means, such as a regulator which controls the voltage applied to the generator. This may be accomplished by interposing in the beam of X-rays, either before or after transmission through an object, a radiation-sensitive device responsive to X-ray intensities and employing such a device to regulate the voltage applied to the generator from a conventional source of alternating current. Such a radiation-sensitive device may consist of an ionization chamber, a phototube-fluorescent screen combination, a selenium cell or any other device that causes an electrical current to flow or which modulates the amplitude of an electrical current or potential in correspondence with the intensity of the radiation received by the device. A regulating system actuated in this manner possesses a very favorable ratio of regulation due to the fact that a given proportional change in supply voltage tends to cause a much greater proportional change in radiation output.

50 It also permits the accomplishment of certain control functions most desirable in the automatic inspection and gauging arts and which cannot be achieved by other equipment.

One of the objects of my invention is to de-

rive a pulse of regulating energy from each pulse of radiation emitted by an X-ray generator. These pulses of radiation are emitted whenever a half-cycle of voltage of the proper polarity is applied to the terminals of an X-ray tube. Each of such pulses of radiation has an intensity which increases from zero to a maximum and then decreases to zero, such variation being in phase with the half-cycle of applied voltage. In the case of a self- or half-wave-rectified generator, the other half of this cycle of applied voltage produces no radiation. The aforesaid pulse of radiation produces a corresponding pulse of ionization current in the ionization chamber (or a corresponding pulse of phototube current in the phototube-fluorescent screen combination). Hence, an impulse of regulating energy is applied to the regulating system in synchronism with each useful voltage impulse received by the X-ray tube. Such a regulator works equally well with self-rectification, half-wave rectification, or full-wave rectification.

Another object of the invention is to provide a novel method and apparatus for gauging or comparing articles by use of X-ray transmission therethrough. A further object is to subject a moving object to a beam of X-rays while maintaining the intensity of the transmitted radiation substantially constant, preferably by control of voltage applied to the X-ray generator. A further object is to provide a novel method and apparatus in which X-ray beams simultaneously traverse an object to be tested and a "standard" object or device, the transmitted beams being compared as a measure of the properties or dimensions of the object being tested. Another object is to provide a novel arrangement for such comparison of beam intensities, e. g., a novel arrangement of two ionization chambers or other radiation-sensitive devices capable both of producing an indication and of effecting regulation of the X-ray generator.

Further objects and advantages of my invention will be evident to those skilled in the art from the following description of exemplary embodiments illustrated in the drawing, in which:

Fig. 1 is a wiring diagram illustrating the general principles of the invention in an exemplary embodiment;

Fig. 2 is a similar wiring diagram illustrating the invention as employed in the gauging or comparing of two objects;

Fig. 3 is a wiring diagram of a circuit alternative to that shown in Fig. 2; and

Fig. 4 is a wiring diagram of an alternative circuit employing an auto-transformer for control of the voltage applied to the X-ray generator.

A general introduction to my invention may be obtained by referring to Fig. 1, with the understanding that those skilled in the art will recognize the control circuit as an electrical network which merely exemplifies a suitable means of utilizing the fundamental principles of my discovery. Various other known control circuits may be similarly actuated and thus employed for accomplishing the objectives of my invention.

I have discovered that an excellent type of regulating energy may be obtained by interposing an ionization chamber 10, or other radiation or X-ray sensitive device, in the path of a beam of ionizing radiation, typically a beam of X-rays 11 from an X-ray generator indicated generally by the numeral 12. In some instances, the beam 11 can be dimensioned by an aperture plate 13 formed of lead or other material substantially

opaque to the radiation, although this is not essential.

That portion of the beam 11 reaching the ionization chamber 10 may have traversed an object 14, such as a standard or test specimen, and been partially absorbed and scattered thereby. Alternatively, the ionization chamber 10 may be positioned directly in the beam from the generator 12, and the radiation passing therethrough may reach an object 15, typically a standard or test specimen, since this arrangement is desirable in certain instances, as discussed hereinafter. This is one of the advantages of using an ionization chamber rather than other types of X-ray-sensitive devices since the ionization chamber 10 may be so constructed as to intercept the entire useful beam of radiation 11 without interposing measurable opacity, thus making the beam available for other purposes. An ionization chamber has the additional advantage that it has a response to X-radiation which is independent of the wave length thereof and independent of the voltage applied to the X-ray tube or the frequency thereof. The ionization current requires more amplification than the regulating current obtained from some other X-ray-sensitive devices, such as certain phototube-fluorescent screen combinations, but the necessary gain may be readily attained without exceeding the limits of stable amplification.

The various components of the voltage regulator exemplified in Fig. 1 are electrically connected in such relationship that the primary voltage supplied to the X-ray generator 12 is inversely controlled by the intensity of the beam 11. This important concept represents one of the fundamental principles of my invention and is utilized in various systems exemplified in the embodiments to be described.

The X-ray generator 12 comprises a primary winding 16, a secondary winding 17 inductively coupled thereto, and an X-ray tube 18 electrically connected in parallel with the secondary winding 17. A modulated or regulated voltage is applied to the primary winding 16 by connecting it to a suitable voltage control device, exemplified as a variable impedance or reactor 20 having a winding 19 connected in series with the winding 16 and having a secondary or control winding 21. The series-connected windings 16 and 19 are electrically connected across an A. C. power line or source of variable A. C. voltage 22. As explained hereinafter, a suitable control means is employed to decrease the voltage drop across the winding 19 of the reactor whenever the ionization current or beam intensity decreases, and vice versa. Hence, the voltage applied to the primary winding 16 increases whenever the ionization current or beam intensity decreases, and vice versa.

If an ionization chamber is used as the radiation-sensitive device, it may be of conventional construction or may be of the improved type shown in my co-pending application, Serial No. 623,334, now Patent No. 2,458,099, issued January 4, 1949. As diagrammatically illustrated in the instant drawing, the ionization chamber provides two electrodes 23 and 24 disposed in a suitable housing capable of transmitting X-rays. The space between the electrodes 23 and 24 contains a gas capable of being ionized by the beam 11. When an intense electrostatic field is maintained between the electrodes by a source of unidirectional voltage, such as a battery 25, an ionization current will flow between the electrodes, this current varying with the intensity of the

incident ionizing radiation. It should be clear that electrodes substantially transverse to the beam 11 are not requisite and that other ionization chambers employing electrodes extending in the general direction of the beam can be employed.

The invention comprehends that the resulting ionizing current be used through any suitable control means to modify the voltage applied to the winding 16 of the X-ray generator. In the instant example, a suitable control means is employed to vary the voltage control device, e. g., the variable impedance or reactor 20, and thus vary the voltage applied to the winding 16 of the X-ray generator, preferably in a manner to maintain the ionizing radiation substantially constant. If the ionizing radiation is measured after transmission through the object 14, it will maintain the transmitted radiation substantially constant irrespective of changes in line voltages, changes in operation of the X-ray tube 18, or changes in opacity of the object 14.

In the arrangement shown in Fig. 1, the ionization current of the ionization chamber 10 is made to control the current through the secondary or control winding 21 of the reactor 20, although it will be clear that other voltage control devices and other control means operatively connecting same to the ionization chamber or other radiation-sensitive device can be employed. In the illustrated control circuit, the output from the ionization chamber is fed to an amplifier 26, the amplifier output being rectified by a diode 27 or other rectifying means, the rectified current being then filtered to any desired extent, as by use of a condenser 28. The voltage across the condenser is applied to a variable-resistance means, such as the winding of a potentiometer 29, having a sliding contact 30 which may be adjusted to control the biasing potential applied to the grid 31 of an amplifying electron tube 32. The grid 31 is energized with such polarity that the biasing potential becomes increasingly negative as the output voltage of the amplifier 26 increases. A suitable B-potential is supplied to anode 33 of the tube 32, as indicated. The cathode 34 of this tube is connected by a conductor 35 to a suitable phase-shifting network 36, included within dotted lines 37.

The phase-shifting network 36 is shown as comprising a variable impedance or reactor 38 with its control winding 39 receiving the output of the tube 32 by being connected between conductor 35 and ground. The main winding 40 of the reactor 38 is connected by conductor 41 to a variable resistor 42 to dispose this resistor in closed circuit with the winding 40 and with a center-tapped secondary winding 43 of a transformer 44 having a primary winding 45 energized from line 22. The center-tapped secondary winding 43 supplies an energizing A. C. voltage to the network, the resistor 42 forming the resistive arm of the network and the winding 40 forming the reactive arm. The reactance of the winding 40 is controlled by the plate current of the tube 32 flowing through control winding 39.

The output of the phase-shifting network 36 is through conductors 47 and 48, respectively connected to the center tap of secondary winding 43 and to conductor 41. These conductors 47 and 48 are connected to the control electrodes of a thyratron 50, namely, to cathode 51 and grid 52. The control winding 21 of the reactor 20 is connected between anode 53 and cathode 51 of the thyratron 50. A resistor 55 is usu-

ally connected across the control winding 21 for a purpose to be later described.

In effect, windings 19 and 21 of the reactor 20 bear the same relation as primary and secondary windings of a transformer so that a flow of alternating current through the winding 19 will induce an A. C. voltage in winding 21, which voltage is impressed between the cathode 51 and the anode 53 of the thyratron 50. In this connection, the thyratron 50 functions as a grid-controlled load across winding 21, and thus the impedance of winding 19 is decreased or increased as the conductivity of the thyratron 50 is increased or decreased, respectively. The conductivity of thyratron 50 is controlled by the action of the phase shifting network 36 in varying the phase angle of the thyratron firing voltage through the variation in the reactance of the winding 40 caused by any change in amplitude of the plate current of the tube 32 flowing through the winding 39.

Normally, the rectified output of the amplifier 26 is adjusted by the sliding contacts 30 to bias the amplifying tube 32 just short of cut-off. Under this condition, the resistor 42 in the phase shifting network 36 is adjusted for operation of the X-ray generator 12 at any desired or predetermined level. Then any factor in the power line 22, X-ray generator 12, or object 14 tending to cause a change in this predetermined level also tends to cause a change in the ionization current which, in turn, alters the biasing potential of the grid 31 of the amplifying tube 32. If there is a decrease in radiation output from the predetermined level, the biasing potential of the grid 31 of the tube 32 becomes less negative, which increases the plate current of the tube. This increased plate current flowing through the winding 39 decreases the reactance of the winding 40, which has the effect of shifting the phase angle of the firing voltage applied to the grid of the thyratron 50 in such direction as to increase its effective conductivity. The increased conductivity of the thyratron 50 reduces the reactance of the winding 19, which causes a greater voltage to be applied to the primary winding 16 of the X-ray generator 12. This action, which is extremely rapid, continues until the intensity of radiation entering ionization chamber 10 is restored to the value that existed before the change in output occurred. The opposite action takes place if the X-ray generator output rises above the predetermined level. Hence, the effective voltage applied to the X-ray generator 12 varies inversely with the ionization current in the ionization chamber 10 in such a way as to maintain at a constant level the intensity of radiation entering the chamber.

The control circuit described hereinabove is suitable for regulating the voltage applied to half-wave or self-rectified X-ray generators since but one thyratron is employed, the reactor 20 being thus saturated during half of each cycle. Incidentally, in the case of self-rectified generators, this control circuit serves as an excellent inverse voltage suppressor, through the action of the resistor 55 connected across the winding 21 and which passes enough energy to collapse the X-ray transformer field during the unused portion of the cycle. This control circuit can be adapted for use with full-wave rectifying equipment by adding a second thyratron and removing the bypass resistor 55.

The circuit of Fig. 1 has a desirably high ratio

of regulation, typically 20:1 or more, whereby its ability to compensate quickly and effectively to maintain the beam intensity at the ionization chamber substantially constant is enhanced. The arrangement of Fig. 1 is useful in many instances where it is desirable that such beam intensity be maintained substantially constant, e. g., in X-ray therapy, thickness gauging, or automatic inspection of materials. In this respect, my invention satisfies a longfelt need because conventional X-ray generators are very sensitive to changes in line voltage. Heretofore, compensation for this critical characteristic has been manual—a tedious procedure involving constant attention and carefully repeated measurements of radiation intensity. In many instances, e. g., in the gauging or automatic inspection of materials, manual compensation is entirely inadequate.

The system of Fig. 1 can be used for gauging by measurement of currents or voltages in various portions of the circuit as an indication of the dimension or characteristic to be determined. For example, the object 14 may be a moving strip of material or different specimens may be placed in the beam to obtain an indication of the thickness or X-ray opacity, the latter being indicative of the character and position of defects.

However, a superior inspection, e. g., gauging or testing for flaws, can be achieved by employing the circuits of Figs. 2 or 3. In addition, such systems can be used, if desired, to compare a test specimen with a standard.

Fig. 2 shows, as before, the X-ray generator 12 and its related control equipment, the elements being indicated by the same numerals as in Fig. 1 so far as applicable. In the system of Fig. 2, however, the total emission of the X-ray tube 18 is divided into, or produces in effect, two beams 70 and 71, respectively directed toward ionization chambers 72 and 73, or other radiation-sensitive devices. If desired, the total emission from the tube 18 can be divided into two separate beams by suitable aperture means, not shown. The ionization chamber 72 is shown as including parallel electrodes 74 and 75, exemplified as substantially perpendicular to the incident radiation of the beam 70. Similarly, the ionization chamber 73 is shown as including electrodes 76 and 77. Articles or objects 80 and 81 are shown as disposed respectively in the beams 70 and 71. To exemplify some of the principles and advantages of the invention, the objects 80 and 81 are shown as wedge shaped and as being synchronously movable through the respective beams in the direction of arrow 82, as by being pushed by an operating member 83. The upper faces of the objects 80 and 81 are shown as substantially perpendicular to the incident radiation.

The electrodes of the ionization chambers 72 and 73 are here connected to a suitable inspection bridge circuit, indicated generally by the numeral 85. In the simplified circuit shown, the ionization chambers 72 and 73 are respectively disposed in arms 86 and 87 of the bridge, the remaining arms being constituted by end sections of a potentiometer winding 88. The previously described source of unidirectional potential 25 is connected between variable arm 88 of the potentiometer and the upper junction of the bridge to form one diagonal of this bridge. Across the other diagonal is connected a suitable indicating means, exemplified as a sensitive galvanometer 90. If the object 80 is to be considered as a standard and the object 81 as a

test specimen, the junction 91 of the bridge is connected to the amplifier 26, the remaining portion of the circuit being as before.

The operation of the circuit of Fig. 2 will be discussed under several conditions. Assume, first, that the control circuit is rendered inoperative to maintain the desired beam intensity, as by disconnecting the amplifier 26, and that the objects 80 and 81 are of uniform thickness throughout their length. Under such conditions, the object 80 may be merely an appropriate radiation filter matched in X-ray opacity to that of the specimen 81 when of desired thickness or character. If the bridge is preliminarily balanced, by adjustment of the potentiometer 88 while an object 81 of desired opacity is present, subsequent insertions into the beam 71 of other test objects or specimens will effect gauging thereof or comparison thereof with the standard object 80. For example, the bridge will be in balance when the object 81 is of the desired standard thickness or its opacity corresponds to that desired. If either more or less radiation is transmitted through the object 81 (e. g., the object is thinner or thicker than standard), the bridge will indicate a corresponding unbalance and the degree of the unbalance will be shown directionally on the galvanometer 90. Similarly, if the object 81 is of substantially uniform thickness and is moved along the beam 71, its thickness or character at various sections can be compared with the standard. If the level of X-ray output from the tube 18 is kept constant, it is possible to calibrate the galvanometer 90 in units of thickness of the object 81 being gauged.

However, even small changes in line voltage may produce marked inaccuracies, as will be understood from the following discussion. If the energy flowing in the bridge under average conditions be arbitrarily assigned a value of 100, and it be assumed that a variation of 1% from standard thickness will cause an unbalance of unity, then a change in line voltage sufficient to increase the intensity of the transmitted radiation 25% will cause a 1% variation from standard thickness to register as a 1.25% variation. Under average conditions, a change in 10% of line voltage may double or halve the transmission, while a change of 5% is often more than enough to change the transmission 25%. Under fixed conditions, an X-ray-thickness gauge is a sensitive, precise instrument capable of measuring variations from standard thickness smaller than 0.2% or one part in 500. However, this sensitivity cannot be achieved with a generator whose output is affected by the usual variations in line voltage since the latter usually amount to several per cent even on the best regulated power lines.

If, under the above conditions, the bridge is connected to the amplifier to render operative the control circuit, the voltage applied to the X-ray generator 12 will be adjusted to compensate for such line variations, and any variations inherent in the X-ray generator 12, to the end that the transmission through the object 80 will be maintained substantially constant. Under such conditions, the invention will maintain an X-ray output whose variation is but a fraction of 1% even if the line voltage varies as great as 20%.

In the industrial X-ray testing of objects, many such objects have a wedge-like configuration from an X-ray point of view. Among some

objects are hollow steel airplane propellers, spar caps for airplanes, ordnance shells, rockets, etc. For this reason, Fig. 2 shows objects 80 and 81 of wedge shape to illustrate the operation of the invention in the inspection of objects having non-uniform cross sections, either for gauging or testing for flaws. In almost all cases the standards of inspection are based upon the proportion existing between the size of a flaw and the thickness of the section at the point where the flaw occurs. These standards are usually expressed in percentages of the total thickness.

The impossibility of achieving satisfactory results with conventional apparatus, when inspecting objects of non-uniform cross section, may be illustrated by the following arbitrary example. Assume that a simple wedge is to be inspected, the wedge being formed of aluminum and having uniform width and a thickness which varies from 4" at the butt to 1" at the tip. Assume that the inspection specifications state that a variation of 5% or more from normal at any point between the butt and tip represents a rejectable object, whether the defect is due to voids, inclusions, or other causes, but that lesser variations are acceptable. A similarly dimensioned aluminum wedge free from flaws will be assumed as used as a standard in the other X-ray beam. Assume, first, that the control circuit is rendered inoperative, as by disconnecting the amplifier 26. As the "standard" wedge, representing the object 80, is moved through the beam 70 and the wedge to be tested, representing the object 81, is synchronously moved through the beam 71, the bridge circuit will indicate, to some extent, flaws or abnormalities in the test wedge. However, the intensity of the incident radiation will be substantially constant, assuming no line voltage variations, and the transmitted radiation through the two wedges will vary markedly from one end of the wedge to the other. The most difficult portion of the wedge in which to reveal a 5% defect is the thick end. Practical experience dictates the need for an X-ray tube voltage of about 200 kv. p. for this 4" thickness of aluminum. Assume that the energy flowing in the bridge is defined as having a level of 100 when the inspection starts at the butt end and that a 5% defect will cause an unbalance of five to be indicated by the inspection bridge circuit 85. Assume, also, that the beams reaching the two ionization chambers are confined, by suitable means, to be relatively narrow in the direction of the length of the moving wedges.

Under such circumstances, the synchronous translation of the wedges through the beams causes the intensity of the transmitted radiation to increase rapidly as the thickness of the wedges decreases. The amount of this increase may be determined by reference to X-ray transmission curves for aluminum sheets of various thickness, which show that the X-ray transmission will increase 550% as the thickness decreases 50%. Hence, at a point where the wedge is 2" thick, the energy flowing in the inspection bridge circuit will be increased to a level of 550 and, consequently, a 5% defect at this point will cause an unbalance equivalent to that produced by a 26.5% defect in the 4" section. In other words, a defect of less than 1% will register here as a 5% defect. Finally, at a point where the wedge is 1" thick, the energy level in the bridge will be increased to 1400 and a 5% defect will appear to be a 70% defect or, stated in another way, a

defect of 1% will register here as 14%. The overall results are thus not usable.

However, if the effective energy level in the inspection bridge circuit 85 is maintained uniform, as by connecting the amplifier 26 and the control circuit as suggested in Fig. 2, very satisfactory inspection can be obtained. This is true even though the relationship between transmission and thickness is not linear and even though this relationship is dependent upon the nature of the material being tested or the complex shape of the object. When using the present invention, the intensity of the transmitted radiation is automatically maintained substantially constant by adjustment of the supply voltage to the X-ray tube 18. These conclusions follow whether the objects 80 and 81 are wedge shaped or whether they have irregular thickness or variable opacity at different sections.

The regulation system is preferably made responsive to the radiation passing through the standard object, e. g., the object 80. The invention continuously adjusts the output of the X-ray generator 12 to maintain the radiation intensity reaching the ionization chamber 72 substantially constant. The intensity of radiation reaching the ionization chamber 73 will vary with the transmission characteristics of the test object and the bridge will indicate accurately the differences between the two objects at related sections thereof. Consequently, by means of the invention, the inspection or gauging of complex materials, e. g., materials having variable chemical or physical characteristics, is rendered as simple and reliable as the inspection or gauging of uniform sheets of homogenous material.

The embodiment of Fig. 3 illustrates a different inspection bridge circuit, outlined by dotted lines 100 and which has the advantage of much greater sensitivity. A circuit of this type is claimed specifically in my copending application, Serial No. 623,335, now Patent No. 2,513,818, issued July 4, 1950, and reference thereto will indicate additional advantages and characteristics over and above those herein briefly described.

Referring to Fig. 3, one terminal of the source of unidirectional potential 25 is grounded at 101. As before, this source energizes both ionization chambers. The output of the ionization chamber 73 is delivered to one end of a potentiometer winding 102, the potentiometer having a variable contact 103 connected to ground through potentiometer winding 104, this potentiometer having a variable contact 105. The output of the ionization chamber 72 is delivered to the input of the amplifier 26 as before and also through potentiometer winding 107 to ground, this potentiometer having a variable contact 108. This variable contact is connected to the grid of an electron tube 110, which acts as a phase-shifting tube. The cathode of this tube is biased by a resistor 111. The tube 110 provides an anode or plate 113 to which a suitable plate potential is applied through resistor 114. The output of the tube 110 is delivered through condenser 116 to the remaining end of the potentiometer winding 102 and appears there, by virtue of the characteristic action of the tube 110, 180° out of phase with the input supplied by the ionization chamber 73. The variable contact arm 108 is adjusted so that, with equal signals supplied by the ionization chambers, the output of the tube 110, appearing at one end of the potentiometer winding 102, is equal to the signal appearing at the other end of the potentiometer winding 102 from the ioniza-

tion chamber 73. Since the thus balanced potentials applied to the ends of the potentiometer winding 102 are equal and of opposite polarity, the potential to ground from the variable contact 103, when at midpoint position, is zero. The variable contact 103 supplies a control potential to a grid of an electron tube 120 whose cathode is appropriately biased by a resistor 122 and whose anode or plate 123 is supplied with anode potential through resistor 124, the output of the tube 120 being fed through condenser 125 to any suitable indicating means 126, which may be a galvanometer similar to that previously described, whether or not preceded by an additional amplifying stage.

The phase inverting nature of the circuit of Fig. 3 will be further apparent from the following description of its operation.

In the arrangement of Fig. 3, the output signals from the two ionization chambers are, in effect, balanced against each other and any differential will set up a directional potential at the variable contact arm 103, which is applied to the grid of the tube 120 and amplified before being delivered to the indicating means 126. In this embodiment, phase inversion is used to enable two signals, arising respectively from the ionization chambers, to be displaced 180° out of phase with each other in order that they may be balanced against each other and a net potential developed to feed a signal to the indicating means 126. The embodiment of Fig. 3 will be found extremely sensitive and well suited to the comparative inspection of objects 80 and 81, the object 80 being a standard. The control portions of the circuit will maintain substantially constant the radiation transmitted by the object 80 and received by the ionization chamber 12. If the test object 81 is strictly comparable at the corresponding section, the inspection bridge circuit will remain in balance, but any disconformity will be indicated greatly magnified, by the indicating means 126.

In installations where transient variations in beam intensity are relatively unimportant, e. g., in X-ray therapy and some types of gauging, a motor-driven-auto-transformer may be employed, as suggested in Fig. 4. While, as previously mentioned, a line-voltage-controlled, motor-driven, auto-transformer is open to objection in many uses, such a transformer can be used with a circuit suggested in Fig. 4 where extremely rapid response is not requisite. This is particularly true if, as in Fig. 4, the auto-transformer is made to adjust the voltage applied to the X-ray generator in response to changes in the intensity of the X-ray beam.

Referring particularly to Fig. 4 the auto-transformer is indicated by the numeral 130 and includes the usual winding 131 connected across the conductors of the line 22. The usual movable contact 132 is movable in opposite directions by a reversible motor 135 having a field winding 133 and an armature 137. The armature is operatively connected to the movable contact 132 by any suitable means. As suggested in Fig. 4 the armature may be connected to a rotating shaft 138 carrying a threaded portion 139 in which is disposed a threaded rod 140. This rod is kept from rotation by any suitable means and is connected to the movable contact 132 to advance and retract same upon respective forward and reverse rotation of the armature 137. The primary winding 15 of the X-ray generator 12 is connected between the movable contact 132

and one end of the winding 131 whereby the voltage applied to the X-ray generator will be varied by forward or reverse rotation of the armature 137.

5 A suitable control is provided for selectively turning the armature 137 in opposite directions upon respective increase and decrease in intensity of the X-ray beam. This control may include the ionization chamber 10 and its immediately associated circuits in the same manner as suggested in Fig. 1, the circuit differing beyond the potentiometer 29. The remainder of the circuit functions to control the operation of the motor 135 in forward or reverse directions, as required to compensate for changes in beam intensity, the showing in Fig. 4 being merely exemplary of numerous control circuits which can be employed without departing from the spirit of the invention.

In Fig. 4, the rectified output of the amplifier 20 26 is applied, through the sliding contact 39, to one end of a resistor 142, the other end of this resistor being connected to a suitable source of B-potential so that a small amount of current is continuously bled through the resistor 142, this 25 current varying with the intensity of the X-ray beam.

Sliding contacts 143 and 144 engage the resistor 142 and supply bias to grids 145 and 146 of triodes 156 and 151. Cathodes 152 and 153 of these 30 triodes are biased respectively by resistors 154 and 155. Anodes 156 and 157 of the two triodes are respectively connected to relay windings 158 and 159 of relays 160 and 161. The remaining 35 terminals of the windings 158 and 159 are connected together by a conductor 162 from which a conductor 163 leads to a source of B-potential for the triodes.

The relay 160 is shown as of the double-pole, 40 double-throw type providing blades 165 and 166 mechanically connected together and to the armature of the relay as suggested by line 167. These blades are also electrically connected by the conductor shown. When the relay 160 is open, the 45 blades 165 and 166 are held in their upper position, shown in Fig. 4, as by a spring 168. In this position the blades respectively engage contacts 169 and 170. When the relay is closed these blades move downwardly to engage, respectively, contacts 171 and 172.

50 Similarly the relay 161 includes blades 175 and 176 mechanically connected as suggested by the dotted line 177. The blades 175 and 176 are normally held in their upper or open position, as by a spring 178, but are shown in their lower or 55 closed position in Fig. 4. The relay 161 also provides contacts 179, 180, 181, and 182, similar in position to the corresponding contacts of the relay 160.

60 The relays 160 and 161 are connected in a reversing circuit functioning to reverse the current in the field winding 136 of the motor 135 to effect opposite rotation of the motor, also to deenergize the motor when no adjustment of voltage to the 65 X-ray generator is required. As shown, the contacts 169 and 179 are connected by a conductor 185. A similar conductor 186 connects the contacts 171 and 181. The contact 170 is connected, by a conductor 187, to one terminal of the field 70 winding 136 and, by a conductor 188, to the contact 182. Similarly, the contact 180 is connected, by a conductor 189, to the remaining terminal of the field winding 136 and, by a conductor 190, to the contact 172.

75 The motor 135 is shown as being of the series

type, the armature 137 being connected in series with one of the conductors 22 of the line, this conductor extending to the blade 175. The remaining line conductor 22 extends to the blade 176.

The operation of the system shown in Fig. 4 is as follows. The sliding contacts 143 and 144 are adjusted on the resistor 142 until the relay 160 is open and the relay 161 is closed, as shown. This is done during the time that the intensity of the X-ray beam is at the desired level. Adjustment of the contacts 143 and 144 changes the grid potentials of the triodes. Due to the relationship of the contacts 143 and 144, the grid 146 of the triode 151 is always less negative than the grid 145 of the triode 150. With this setting of the relays, both the armature and field circuits of the motor 135 are open so that the armature 137 does not turn.

If the intensity of the X-ray beam increases, the grid 146 becomes more negative thus decreasing the anode current through the winding 159 and opening the relay 161, the relay 160 remaining open. At this time current flows through the armature 137, blade 175, contacts 179 and 169, blades 165 and 166, contact 170 and conductor 187 to the lower terminal of the field winding 136. The return circuit is from the upper terminal of this field winding through the conductor 189, contact 180 and blade 176. This energizes the field winding 136 in one direction and causes the motor to turn in a forward direction to decrease the voltage supplied to the X-ray generator. This reduces the intensity of the X-ray beam to the normal level, at which time the relay 161 closes to deenergize the motor.

Conversely if the intensity of the X-ray beam falls below normal, the potential of the grid 145 becomes more positive with the result that the anode current in the triode 150 increases to close the relay 160, the relay 161 remaining closed. Current then flows through the armature 137, blade 175, contacts 181 and 171, blades 165 and 166, contact 172 and conductors 190 and 189 to the upper terminal of the field winding 136. The return circuit is from the lower terminal of this field winding through conductors 187 and 188, contact 182 and blade 176. This reverses the current through the field winding, as compared with the previous example, and rotates the armature 137 in the opposite direction to increase the voltage applied to the X-ray generator. As before, the motor 135 stops when the intensity becomes normal and the relay 160 opens.

It should be understood that various radiation-sensitive devices other than ionization chambers can be employed. It should also be clear that voltage control devices other than a saturable reactor or a reversible motor can be employed and that other types of control means can be employed to vary the voltage control device in response to signals from the radiation-sensitive device. The illustrated arrangements are merely exemplary of a number of voltage control systems which may be used to vary the voltage applied to the X-ray generator, and the invention comprehends any suitable voltage regulation system connected, for example, to the output of amplifier 26 for varying the voltage applied to the X-ray generator in such way as to maintain substantially constant the radiation intensity in some portion of the beam.

The present description will be exemplary of other uses and modifications of the invention, which will be apparent to those skilled in the

art and which are comprehended in the scope of the appended claims.

I claim as my invention:

1. In combination in a system for maintaining substantially constant the radiation intensity of an X-ray generator at a given position in the beam of X-rays produced thereby: radiation-sensitive means at said given position and responsive to variations in radiation intensity of said beam at said position; and means for controlling the voltage applied to said X-ray generator to maintain said radiation intensity at said position substantially constant, said means comprising a voltage control device for controlling the voltage applied to said generator and including a control means operatively connected to said radiation-sensitive means and said voltage control device for varying said voltage applied to said generator to maintain said radiation intensity at said position substantially constant.

2. A combination as defined in claim 1, in which said voltage control device comprises a variable impedance including a winding connected to said X-ray generator to vary the voltage applied thereto and a control winding, said windings being inductively coupled, and in which said control means includes means for changing the current flowing through said control winding in response to changes in radiation intensity at said position.

3. A combination as defined in claim 1, in which said voltage control device comprises a variable impedance including a winding connected to said X-ray generator to vary the voltage applied thereto and a control winding, said windings being inductively coupled, and in which said control means includes a grid-controlled tube for varying the current flowing through said control winding and means operatively connecting the grid of said tube to said radiation-sensitive means.

4. A combination as defined in claim 1, in which said voltage control device comprises a variable impedance including a winding connected to said X-ray generator to vary the voltage applied thereto and a control winding, said windings being inductively coupled, and in which said control means includes a grid-controlled tube for varying the current flowing through said control winding and a phase shifting network operatively associated with said radiation-sensitive means for controlling the grid voltage of said tube.

5. A combination as defined in claim 1 for the comparative inspection of a test object and a standard object and in which said X-ray generator produces said beam and another beam of X-rays each directed toward one of said objects to be partially absorbed thereby and to produce a transmitted beam transmitted therethrough, said radiation-sensitive means at said given position being within one transmitted beam to be responsive to the radiation transmitted by the corresponding object, and including another radiation-sensitive means in the other transmitted beam to be responsive to the radiation transmitted by the corresponding object, and means for comparing the outputs of said two radiation-sensitive means to obtain a measure of the disconformity between said test object and said standard object, said control means operatively connecting said voltage control device to at least one of said radiation-sensitive means.

6. A combination as defined in claim 1 for the comparative inspection of a test object and a

standard object and in which said X-ray generator produces two beams each directed toward one of said objects to be partially absorbed thereby and to produce a transmitted beam transmitted therethrough, said radiation-sensitive means at said given position being within the transmitted beam of said standard object to maintain the intensity of this transmitted beam substantially constant, there being another radiation-sensitive means in the transmitted beam of the test object, and including means for comparing the outputs of said two radiation-sensitive means to obtain a measure of the disconformity between said test object and said standard object.

7. A combination as defined in claim 6 for the testing of a test object of variable X-ray opacity throughout its length, and including means for progressively moving said test object relative to its X-ray beam.

8. A combination as defined in claim 6 for the testing of test and sample objects each of different X-ray opacity at different sections thereof, and including means for synchronously moving both said objects relative to their respective X-ray beams to move the sections of both objects sequentially through the respective X-ray beams, said comparing means including circuit means for producing a potential varying with the disconformity between the test object and the standard object at corresponding sections thereof.

9. A combination as defined in claim 6 in which said comparing means includes a bridge circuit connected to said two radiation-sensitive means, said bridge circuit including means for producing a potential varying with the disconformity between said test object and said standard object.

10. A combination as defined in claim 6 in which each of said radiation-sensitive means is an ionization chamber, and in which said comparing means includes a bridge circuit connected to said ionization chambers, said bridge circuit including means for producing a potential varying with the disconformity between said test object and said standard object.

11. A combination as defined in claim 6 in which the voltage control device comprises a variable impedance including a winding connected to said X-ray generator to vary the voltage applied thereto and a control winding, said

windings being inductively coupled, and in which the control means includes means for changing the current flowing through said control winding in response to changes in radiation intensity received by said radiation-sensitive means at said given position.

12. A combination as defined in claim 6 in which the voltage control device comprises a variable impedance including a winding connected to said X-ray generator to vary the voltage applied thereto and a control winding, said windings being inductively coupled, and in which the control means includes a grid-controlled tube for varying the current flowing through said control winding, and means operatively connecting the grid of said tube to said radiation-sensitive means at said given position.

13. A combination as defined in claim 6 in which the voltage control device comprises a variable impedance including a winding connected to said X-ray generator to vary the voltage applied thereto and a control winding, said windings being inductively coupled, and in which the control means includes a grid-controlled tube for varying the current flowing through said control winding, and a phase-shifting network operatively associated with said radiation-sensitive means at said given position for controlling the grid voltage of said tube.
